GOLF BALL PUTTER

Paul Norwood, Hialeah, Fla., assignor to
Miami Golf Products, Inc.

Filed July 15, 1965, Ser. No. 86,173

Term of patent 14 years

(Cl. D34—5)

FIGURE 1 is a side elevational view of a golf ball putter showing my new design, the side opposite being similar in appearance;

FIGURE 2 is a front elevational view thereof;

FIGURE 3 is a cross-sectional view taken along the line 3—3 in FIG. 2;

FIGURE 4 is a bottom plan view of the putter head;

FIGURE 5 is a partial rear elevation view of the putter head;

FIGURE 6 is a side elevation view of the putter head; and

FIGURE 7 is a plan view in cross section of the handle of the putter taken in the plane of the line 7—7 of FIGURE 2 and looking in the direction of the arrows.

I claim:

The ornamental design for a golf ball putter, as shown and described.
